UNITED STATES PATENT OFFICE

172,908

PLAY SUIT OR THE LIKE

Edward Schultheiss, New York, N. Y.

Application February 27, 1953, Serial No. 23,812

Term of patent 3½ years

(Cl. D3—17)

To all whom it may concern:

Be it known that I, Edward Schultheiss, a citizen of the United States and a resident of the city of New York, county and State of New York, have invented a new, original, and ornamental Design for a Play Suit or the like, of which the following is a specification, reference being had to the accompanying drawing, forming part thereof.

In the drawing:

Fig. 1 is a front view of a play suit or the like embodying my new design;

Fig. 2 is a rear view thereof.

I claim:

The ornamental design for a play suit or the like, as shown.
